UNITED STATES PATENT OFFICE.

ANTON CHARLES KORCINEK, OF NEW YORK, N. Y., ASSIGNOR TO AMERICAN DESIGNING & REPRODUCING COMPANY, OF NEW YORK, N. Y., A CORPORATION OF NEW YORK.

METHOD OF MANUFACTURING DRUMMERS' SAMPLES FOR TEXTILE FABRICS.

No. 918,169.

Specification of Letters Patent.

Patented April 13, 1909.

Application filed July 11, 1907, Serial No. 383,254. Renewed March 2, 1909. Serial No. 480,969.

To whom it may concern:

Be it known that I, ANTON CHARLES KORCINEK, a citizen of the United States, and a resident of the city of New York, 5 county of New York, and State of New York, have invented a new and useful Improvement in Methods of Manufacturing Drummers' Samples for Textile Fabrics, of which the following is a specification.

10 My invention relates to samples or specimens of textile fabrics containing designs in different colors, used by drummers and traveling salesmen in soliciting orders in that line of business, and its object is to produce such 15 a sample or specimen prior to the production of the fabric itself, which may be exhibited to prospective customers, and if the design meets with favor, orders may be taken and the goods subsequently manufactured, 20 whereas if the design does not meet with favor, it may be discarded and no loss will be suffered except for the comparatively small cost of making the design. Heretofore it has been the universal custom in selling textile 25 fabrics containing the designs to first manufacture the goods containing the design, in quantities, and then cut off a small sample thereof to be pasted on paper and taken around by the drummer to be exhibited to 30 prospective customers. If orders are secured for goods of any particular design they are filled by the manufacturer from the stock in hand theretofore manufactured, whereas if no orders are taken, the goods already manufactured become a dead loss. According to 35 my invention, I make in advance a small specimen or sample of the new design upon a textile fabric prior to the manufacture of the goods themselves and presenting the same 40 appearance as the manufactured goods, so that the drummer can exhibit this specimen to prospective customers, and if he secures orders therefor the goods are subsequently manufactured to fill the orders; whereas if 45 no orders are secured for a particular design, no goods containing that design will be manufactured, and the only loss suffered will be the comparatively small cost of making the design. Such practice as this has heretofore 50 never been carried out, and I am the first in the art to inaugurate it.

In carrying out my invention the artist first makes the design in colors on paper by hand and the same is then traced in black 55 and white on tracing paper. A photo-

graphic negative on a wet plate is then made of this tracing, which negative is afterward transferred to a lithographic stone in the following manner: The stone is first coated with a light sensitive solution of egg albumen, 60 bi-chromate of ammonia, and water; then the negative is securely clamped to the stone on the surface thereof and exposed to light, preferably an electric light, for about five minutes. This prints the negative on the stone. 65 Impressions on paper are then printed from the stone, as many separate impressions as there are separate colors in the design. This paper impression is dusted over with red chalk, which adheres only to the ink, and it 70 is then pressed onto another prepared lithographic stone and the outlines of the design are thus delineated on the stone by the red chalk marks. There is a separate impression on each stone for each color in the design. 75 The artist then takes these various offsets and on each one paints in with black lithographic ink the space allowed for its particular color in the design, after which the stone is etched with nitric acid so as to reproduce the particular color, and passed through a press. By passing over these stones in succession a piece of fabric in a press the design will be imprinted upon the fabric 80 in fast colors and the result will thus be a 85 complete fac-simile of the original design. It is then pasted onto a piece of paper and is ready for exhibition by the drummer to his prospective customers. The cost of producing this design is comparatively small, and if 90 it does not prove salable it can be thrown away without further loss to the manufacturer.

I am aware that it is old to use lithographic stones, zinc or other such plates for 95 printing in colors on paper, but in such case transfer sheets of a hard unimpressible substance—such as celluloid—are first made, and upon them the different colors are produced by hand, after which the portion of the design on each such sheet is transferred to the printing surface of stone, zinc, or other such material, which is etched in the usual manner, and therefrom the print is made. Such process is long, laborious, tedious, and expensive. 100 In it no use is made of photo-lithography. My invention differs from the above in two particulars, viz: (1) in the printing of colored designs on textile fabrics in fast colors for the production of a drummer's 105 110

sample, and (2) in the use of photo-lithography, instead of the old hand process of the artist.

What I claim, and desire to secure by Letters Patent is:

The method of making a facsimile sample of a textile fabric print, consisting in first, tracing in black on paper the complete pattern, second, photographing the same, third, transferring said photographic negative to a lithographic stone, fourth, taking as many impressions therefrom as there are colors in the design, fifth, transferring these impressions to as many printing surfaces as there

are colors in the design, sixth, painting on each surface the design for its assigned color, seventh, etching said several designs, eighth, applying the selected colors to said several designs, and ninth, pressing a plain textile fabric sample upon said surfaces successively in registering position to reproduce the complete original design.

In testimony whereof, I have hereunto set my hand this 6th day of July, 1907.

ANTON CHARLES KORCINEK.

In presence of—

J. H. MILLER,
CATHARINE HENRY.
